US00D547352S

(12) **United States Design Patent** (10) **Patent No.:** **US D547,352 S**
Tako (45) **Date of Patent:** **** Jul. 24, 2007**

(54) **PROJECTOR**

(75) Inventor: **Hirotaka Tako**, Tokyo (JP)

(73) Assignee: **Sony Corporation**, Tokyo (JP)

(**) Term: **14 Years**

(21) Appl. No.: **29/241,635**

(22) Filed: **Oct. 31, 2005**

(30) **Foreign Application Priority Data**

Aug. 8, 2005 (JP) D2005-022957

(51) **LOC (8) Cl.** **16-02**

(52) **U.S. Cl.** **D16/230**; D16/221; D16/225

(58) **Field of Classification Search** D16/205,

D16/208, 213, 221, 225, 229, 230, 231, 234;

D21/514; 353/70, 100, 101, 115, 119, 122

See application file for complete search history.
